FASTENING INSERTING MACHINE

Filed Sept. 28, 1927

2 Sheets-Sheet 2

UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed September 28, 1927. Serial No. 222,642.

This invention relates to fastening inserting machines, and is illustrated as embodied in a machine arranged to sever fastenings from a strip of fastening material and to insert the fastenings in shoe parts.

My co-pending application for Letters Patent of the United States, Serial No. 34,838, filed June 4, 1925, discloses and claims the fastening together of shoe parts by means of fibre pegs illustrated as severed from paper twine and driven into the shoe parts. This manner of securing together shoe parts has proved to be successful for a number of different operations performed in the manufacture of boots and shoes, and it has become apparent that in order to utilize it to the best advantage a number of different types of fastening inserting machines are necessary. Up to the present time it has been found to be necessary to provide all these machines with means of some sort to form holes in the work for reception of the paper pegs and with means for severing the pegs from the paper twine.

It is an object of the present invention to simplify the mechanism with which such machines are provided for forming fastening receiving holes in the work piece, severing fastenings from twine and driving the severed fastenings into the holes formed in the work piece. With this object in view a characteristic feature of the invention is the organization of the machine in such a manner that the driver acts also to sever the pegs from the twine, and as an awl to form fastening receiving holes in the work piece. The illustrated machine, which constitutes a preferred embodiment of the invention, is provided with a gang of drivers arranged simultaneously to insert a plurality of paper pegs to attach a rand to a heel element. In this machine each driver passage is of a cross-section conforming to that of the paper peg to be inserted, and a second passage of similar cross-section intersects each driver passage to guide a strip of paper twine thereto. In the operation of the machine each driver is reciprocated to form a fastening receiving hole in the work and to withdraw from the hole thus formed. Then the strips of paper twine are fed forwardly into the driver passages whereupon the drivers again descend, each driver severing a peg from the paper twine projecting into its driver passage and driving the peg

into the corresponding hole in the work piece.

While the invention is, for illustrative purposes, disclosed herein with reference to a gang machine organized to insert paper pegs, it should be understood that in various of its aspects it is limited neither to a gang machine nor to a machine for inserting paper pegs.

With the above and other objects and features in view, the invention will now be described with reference to the accompanying drawings and pointed out in the claims.

In the drawings,

Fig. 1 is a side elevation of a fastening inserting machine embodying the present invention and organized to attach rands to heel bases;

Fig. 2 is a front elevation of the machine of Fig. 1;

Fig. 3 is a front elevation on a larger scale than Fig. 2 of the fastening severing and inserting instrumentalities of the machine, part of the machine being shown in cross-section; and

Fig. 4 is a horizontal section on the line IV—IV of Fig. 2.

The illustrated fastening inserting machine is provided with a standard or column 10 carrying at its upper end a pair of shafts 12 upon each of which are mounted four reels 14 of paper twine 16 from which are cut pegs 85 of the character described in said co-pending application, Serial No. 34,838. From the reels 14 the paper twine 16 passes about rods 18, 20 carried by inclined arms 22 pivotally mounted on a rod 24 carried by a plate 26 secured to the top of the column 10. Arms 22 are urged upwardly by springs 28 to apply a certain amount of tension to the paper twine 16 as the latter is fed from the reels. The construction just described is duplicated upon opposite sides of the machine. From the rods 20 the twine 16 passes through openings 30, one of which is formed in each of a plurality of links 32 pivoted at 34 to the column 10 of the machine. Each link 32 carries an idle roll 36 pressed toward a driven feed roll 38 by a spring 40 and is thereby held in engagement with the paper twine which passes between the rolls 36 and 38 and is fed thereby. The four feed rolls 38 on the left side of the machine are all mounted upon a shaft 42 while those at the right are mounted upon a shaft 44. Spur gearing 46 connects the shafts 42

and 44 so that the latter is driven from the former. The shaft 42 is provided also with a ratchet 48 engaged by a pawl 50 carried by an arm 52 connected by a link 54 to a lever 56 fulcrumed at 58 to the column 10 and carrying a cam roll 60 operating in a cam track 62 formed in a cam member 64 carried by a suitably driven shaft 68 having a bearing in the column 10. A spring 70 connected at one end to the tail of the pawl 50 and at the other end to the link 54 tends to hold the pawl 50 in engagement with the ratchet 48 so that the paper twine 16 is fed step by step as the pawl 50 is oscillated. In order to control the length of the twine fed by each movement of the feed rolls 38, the link 54 is connected to the lever 56 by an adjustable bolt and slot connection 72.

From the feed rolls 36, 38 the strips of paper twine 16 pass through flexible tubular guide members 74 to passageways 76 (Fig. 3) formed in a nailing die 78 and intersecting with driver passages 80 of the nailing die. The passageways 76 through which the paper twine is fed and the driver passages 80 correspond in cross-section to the cross-section of the paper twine and are illustrated as circular.

A gang of drivers 82 is carried by a head 84 mounted on a plunger 86. The plunger 86 is provided with a rack 88 (Fig. 1) engaging a gear segment 90 carried by a bell crank lever 92 fulcrumed at 94 to the column 10 and having a depending arm provided with a cam roll 96 positioned in cam track 98 formed in the cam member 64. Thus the gang of drivers 82 is caused to reciprocate through the driver passages 80 in timed relation to the operation of the feed rolls 38. The cam track 98 is so formed that the drivers 82 are first given a long stroke, acting as awls and punching fastening receiving holes 100 in the work piece presented to the nailing die 78 and illustrated in Fig. 3 as a heel base 102 and a rand 104. Then the drivers 82 are withdrawn, the strips of twine fed forward into the driver passages 80 and the drivers 82 again moved downwardly, each driver having a short stroke effective to shear a paper peg 106 from the corresponding strip of paper twine and to force the peg downwardly through the driver passage into the appropriate hole 100 in the work piece.

The work piece to be operated upon may be supported in any suitable manner. As illustrated, the machine is provided with a slide 110 (Fig. 1) mounted for horizontal movement in ways 112 carried by the frame of the machine and provided on its under surface with a rack 114 engaging with a suitably oscillated gear segment 116. The slide 110 carries a work table 118 on which is placed the heel and rand which are to be pegged together. A lever 120 fulcrumed at 122 to the slide 110 carries at its left-hand end (as

viewed in Fig. 1) a clamp plate 124 arranged to engage the central portion of the heel base 102 (see Fig. 4), and having projections 126 positioned to engage the rand in such a manner as not to interfere with the insertion of the fastenings. A spring 128 tends to rock the lever 120 in a counter-clockwise direction as viewed in Fig. 1 so as to clamp a heel and rand upon the table 118. When the slide 110 is withdrawn to the position shown in Fig. 1, however, a depending finger 130 carried by the lever 120 engages a stationary but adjustable stop 132 and rocks the lever 120 in a clockwise direction, compressing spring 128 and holding the clamp 124 away from the work table 118 so that a heel base and rand may be inserted. When the slide 110 is moved to the left to bring the heel and rand into alignment with the nailing block, the finger 130 leaves the stop 132 and the clamp plate 124 is moved downwardly by the spring 128 into engagement with the work.

As illustrated, a die composed of two sections 140, 142 is pivoted at 144, 146 to a bed member 148 carried by the column 10. When the slide 110 is in its forward position as shown in Fig. 1 the die members 140, 142 are moved forwardly about pivots 144, 146 by a spring-pressed plunger 150 at which time the entrance of the die members 140, 142 is considerably wider than the heel base to be operated upon. When, however, the slide 110 is moved rearwardly, the heel base 102 engages the die members 140, 142 and forces them to the position of Fig. 4 prior to the downward movement of the nailing die 78.

As illustrated, a knife 160 is adjustably secured to a carrier 162 (which supports the nailing die 78) so as to trim the forwardly projecting ends of the rand 104. The carrier 162 is mounted for vertical movement between suitable guides 164 carried by the column 10, and is provided with an upwardly extending arm 166 (Fig. 1) carrying a cam roll 168 operating in a cam track formed in the front of the cam member 64.

When the slide 110 is moved forwardly to the position of Fig. 1 after a group of pegs have been inserted to attach a rand to a heel base, the knife 160 is still positioned in front of the heel base and sweeps the latter from the table 118 as table moves forwardly, the heel base 102 and the rand 104 attached thereto dropping through an opening in the bed member 148 to a chute 170 (Fig. 2).

Having thus described my invention what I claim is new and desire to secure by Letters Patent of the United States is:

1. A machine for inserting fastenings having a driver passage, means for feeding fastening material to the driver passage, a driver, and means for reciprocating the driver through the driver passage arranged to cause the driver to form fastening receiving holes in work pieces presented thereto, to

sever fastenings from the fastening material, and to insert the severed fastenings in the holes.

2. A fastening inserting machine having a
5 nailing die provided with a plurality of fastening receiving openings, a gang of drivers, means to feed fastening material to each of the openings, and means for reciprocating the drivers through said openings, said material
10 feeding means and driver reciprocating means being constructed and arranged to cause the drivers to form fastening receiving holes in work pieces presented thereto, to sever fastenings from the fastening material, and to insert the severed fastenings in
15 the holes.

3. A machine for inserting fastenings having a driver passage, means for feeding fastening material to the driver passage, a shear
20 member past which the fastening material is fed, a driver reciprocable through the driver passage, and means for actuating the driver arranged to cause the driver to act as an awl to form fastening receiving holes in work
25 pieces presented thereto and to cooperate with the shear member to sever fastenings from the fastening material.

4. A fastening inserting machine having
30 a nailing die provided with a plurality of fastening receiving openings, a gang of driv-

ers reciprocable through said openings, means to feed fastening material to each of the openings, shear members past which the fastening material is fed, and means for actuating the drivers arranged to cause the drivers to act as awls to form fastening receiving holes in a work piece presented thereto and to cooperate with the shear members to sever fastenings from the fastening material and insert them into the work piece. 40

5. A machine for inserting paper pegs in shoe parts having a work engaging member provided with a driver passage, a driver reciprocable therethrough, a second passage intersecting the driver passage to guide a strip 45 of paper fastening material thereto, means for feeding a strip of fastening material through said second passage into the driver passage, and means for reciprocating the driver arranged to cause the driver to form 50 a fastening receiving hole in the work piece, then to be withdrawn while the strip of fastening material is fed into the driver passage and then to be moved forward to sever a paper peg from the strip of fastening material and to insert the peg thus severed in the work piece. 55

In testimony whereof I have signed my name to this specification.

FRED N. LA CHAPELLE.
